UNITED STATES PATENT OFFICE.

FRANK G. NEWELL, OF ROCHESTER, NEW YORK.

DESIGN FOR A MIRROR OR PICTURE FRAME.

SPECIFICATION forming part of Design No. 14,126, dated July 24, 1853.

Application filed June 14, 1853. Term of patent 3½ years.

To all whom it may concern:

Be it known that I, FRANK G. NEWELL, of the city of Rochester, in the county of Monroe and State of New York, have invented or produced a new and original Design for Mirror and Picture Frames; and I do hereby declare that the following is a full, clear, and exact description of the same, reference being had to the accompanying drawings, in which—

10 Figure 1 is a front elevation of a mirror-frame, showing my new design. Fig. 2 is a side or edge elevation of the same.

The distinguishing feature of this invention is a square mirror or picture frame standing cornerwise, or with two of its corners vertical and two horizontal, and legs on each side of the lower corner, of ornamental form, and moldings on each side of the upper corner, also of ornamental form, the horizontal corners being left plain, as hereinafter described.

15 In the drawings, A shows a square mirror or picture frame of ordinary form. Instead of being set straight, however, as usual, it is set cornerwise, two of the corners standing vertically and two horizontally, as shown in Fig. 1.

20 B are legs secured to the sides of the frame, one on each side of the lower corner, and form-

ing the support for the frame. They are of the ornamental shape shown, consisting of a scroll, 30 a, having a rounded outer end, b, which forms the leg proper, and a body, c, fitting the side of the frame, and provided with ornaments d d d at the outer edges.

CC are ornaments at the top of the frame, 35 one on each side, consisting of blocks with scalloped and notched edges, which relieve the plain surface of the frame and add to its attractive appearance.

What I claim as new is—

40 1. A design for mirror and picture frames, consisting of a square frame set cornerwise, and ornamental supporting-legs at the bottom, one on each side of the lower corner, as herein shown and described.

45 2. A design for mirror and picture frames, consisting of a square frame set cornerwise, ornamental supporting-legs at the bottom, one on each side of the lower corner, and ornamental blocks at the top, one on each side of the upper corner, as herein shown and described.

FRANK G. NEWELL.
